WATER PURIFYING AND DEGASIFYING APPARATUS

Victor A. Rohlin, Philadelphia, Pa., assignor to
Cochrane Corporation, Philadelphia, Pa., a
corporation of Pennsylvania

Application July 20, 1935, Serial No. 32,330

7 Claims. (Cl. 210—14)

The general object of the present invention is to provide an improved method of and improved means for heating, for purifying, and for de-aerating or, more accurately, for degasifying water for boiler feed and analogous purposes. More specifically, the object of the present invention is to provide an improved method and apparatus for subjecting water to a so-called hot process water softening treatment and to a degasifying treatment separating from the water the air initially contained therein and the gases liberated from the water by said treatment.

In accordance with the present invention, the water treated is passed successively through an initial heating stage, an intermediate sedimentation stage, and a final degasifying stage, and is brought into intimate contact with and heated by steam in the initial heating stage, and is subjected to a steam jet atomizing action by which water is sprayed into the final degasifying stage. In the preferred form of the invention, all of the steam used for heating the water in the initial heating stage and in atomizing and spraying the water into the final degasifying stage, is initially supplied to one of the two last mentioned stages, and the steam supplied to and not condensed in the stage to which the steam is initially supplied, is passed to the other of the two last mentioned stages, from which the air and other gases liberated in both stages are discharged.

A primary advantage of the invention arises from the compactness and relatively small bulk and low inherent cost of construction of the apparatus required for the use of the invention. That advantage may be obtained with apparatus in which the steam is initially supplied to the initial heating stage, and with somewhat different apparatus in which steam is initially supplied to the final degasification stage. Whether the steam is initially supplied to one end stage or the other, the initial heating, the softening, and the atomizing and degasification treatments or stages are preferably carried out in a single tank structure which encloses the relatively large sedimentation space required, and has its upper portion partitioned to form an initial steam and water contact heating space, alongside a degasification chamber separated from both of said spaces, except for a port or ports for the passage of water into said chamber from the sedimentation space, and for the passage of steam and gases in one direction or the other between said chamber and heating space.

The invention is further characterized by the provision of means for so regulating the amount

of water maintained in the apparatus, and for so supplying the atomizing steam used, that a gravitational movement of the water out of the sedimentation space will bring the water into the path of an atomizing steam jet flow, and that the latter will give an upward movement to the atomized water, with the resultant advantage that the water level in the storage space of the degasification chamber may normally be but little below the main water level in the tank, so that the atomizing and degasifying operation results in but a trifling loss in water head.

The practical importance of the small loss of water head thus made possible, will be realized when account is taken of the relatively great bulk and height of hot process water purification apparatus units. The sedimentation tank structure of such a unit quite commonly is fifteen or twenty feet or more in diameter, and has a vertical dimension of twenty to thirty feet, and the location of ordinary forms of water heating and degasifying structures above the sedimentation space would extend the vertical dimension of the unit upwardly for a distance which might well be ten or fifteen feet or more. The location of the heating and degasifying means within the tank enclosing the sedimentation space in accordance with the present invention results in an appreciable economy in the space requirement of a unit of given capacity, and reduces its maximum vertical dimension to the sum of that required for sedimentation and for the initial water heating treatment, since the body of water undergoing sedimentation extends and in effect forms the bottom of the initial water heating space.

The height to which the water must be pumped to move it through my improved apparatus is thus reduced practically to the minimum possible, and practically all of the water head created in elevating the water into the apparatus is available for use in passing water from the apparatus into a boiler or other receiving apparatus directly, or more usually, through the filter means required to eliminate the portion of the precipitated impurities not settling out of the water in the sedimentation space.

The degasifying portion of my improved apparatus may be relatively compact as the water loses little heat in passing to it from the initial heating space so that the heating duty of the degasifying apparatus is relatively light, and its continuous operation at practically maximum efficiency is not interfered with by any accumulation of solid impurities from the water, since the

portion of the impurities which the water carries out of the sedimentation space and into the degasifying apparatus is in such form that it passes out of the degasifying apparatus with the water discharged therefrom.

The direct passage of the water from the initial heating space into the sedimentation space through a horizontal flow area which may be the full horizontal area of the said heating space 10 practically precludes any significant reduction of said flow area by the accumulation of deposited impurities. Moreover, when the initial heating action is effected in the preferred manner by spraying the water to be heated and treated into 15 the steam filled heating space D, the deposit of precipitated impurities is mainly restricted to deposit on the walls and in the sludge collecting bottom portion of the sedimentation space from which they can be removed in the same manner 20 as in, and with no more difficulty than is involved in, the operation of any ordinary hot process water purifying unit not provided with self contained water heating and degasifying means.

My improved apparatus is characterized not 25 only by its compactness, but also by inherent simplicity in construction and arrangement, and is inherently relatively inexpensive to construct and maintain.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described preferred forms of apparatus for use in the practice of the invention.

Of the drawings:

40 Fig. 1 is a sectional elevation of one apparatus embodiment of the present invention.

Fig. 2 is a section of a portion of the apparatus shown in Fig. 1, the section being taken on the broken line 2—2 of Fig. 1.

45 Fig. 3 is a sectional elevation of a second form of apparatus for use in the practice of the method claimed herein.

Fig. 4 is a partial sectional plan, the section being taken on the line 4—4 of Fig. 3; and

50 Fig. 5 is a section on the broken line 5—5 of Fig. 4.

In the drawings, and referring first to the apparatus shown in Figs. 1 and 2, A represents a tank in which the water heating, chemical 55 treating, settling, and degasifying operations are performed. The upper portion of the space within the tank A is divided into a water heating space or chamber B and a deaerating chamber or compartment C. As shown, the chambers 60 B and C are separated from one another by a vertical partition A'. The latter extends downward to a level below the normal water level and is connected at its lower end to a transverse partition or wall A² which forms the bottom wall 65 of the compartment C. The bottom of the space B is formed, in effect, by the water body in the sedimentation space. The latter occupies all of the tank interior excepting the portions forming the space B and chamber C.

70 In the apparatus shown in Figs. 1 and 2, the water treated is discharged into the space B through a spray device D comprising a vertical spray pipe extending downward into the space B through the top wall of the tank A and formed 75 with suitable spray discharge orifices D' located

within the space B. The spray device may be, and as shown is of the type disclosed in the Kit-tredge Patent 1,996,159 granted April 2, 1935. The water to be treated is supplied to the spray device D through a supply pipe E connected to 5 the water inlet of a vent condenser F, and a pipe E' leading from the water outlet of the vent condenser to the spray device. The supply of water to the pipe E is controlled by a valve E² operated through a link E³ by a pivoted float E⁴, which floats on the water in the chamber C, and operates through the valve E² to regulate the supply of water as required to maintain an approximately constant water level in the chamber C. The treated water is discharged from the tank 15 A through the outlet H opening from the chamber C below the water level therein. Air and other gases separated from the water, and steam supplied to, and not condensed in the chamber C, are discharged from the latter through the vent 20 or outlet I to the inlet of the condensing space of the vent condenser F, and pass from said space through an outlet F'. The latter may open directly to the atmosphere when the working pressure in the chamber C is to be maintained 25 above that of the atmosphere, and when the working pressure in the chamber C is to be lower than the pressure of the atmosphere, the outlet F' may be connected to any suitable exhauster, in accordance with the usual practice of the art. 30

The steam used in the tank A is supplied to the latter through an inlet J opening to the chamber or space B. The steam may be supplied at any suitable available pressure. Usually the steam supplied is exhaust steam at a pressure slightly above that of the atmosphere. Un- 35 desirable deflection of the jets of water discharged through the orifices D' by the entering steam, is prevented by a baffle J' depending from the top wall of the tank in front of the inlet J. Steam supplied to, but not condensed in the space B, along with air and other gases liberated from the water in that space, pass to the chamber C through a port K in the partition A' along with water passing from the sedimentation space into 40 the chamber C. As hereinafter explained, the part K is, in effect, the inlet part of a deaerating atomizer delivering the water to the chamber C in a fine spray or mist. As shown, the water passing to the port K is conveyed to the latter 45 through a conical collector or draw-off element L, such as is frequently employed to draw off water from the lower portion of a settling chamber or sedimentation space. The collector L is open at its lower end and is connected at its 50 upper end by pipes L' to a compartment or pocket L², the end walls of which are formed by opposed portions of the tank body, and one side wall of which is formed by the partition A'. The other side wall and the bottom wall of the pocket L² 55 are formed by vertical and horizontal portions, respectively, of a partition member L³. The latter extends nearly to the top of the tank A and serves as a baffle preventing the water spray discharged through the orifices D' from entering 60 the space L², while permitting steam not condensed in the space B, and air and other gases liberated from the water and passing into admixture with uncondensed steam, to pass into the compartment L² over the top of the partition 65 L³.

As previously stated, the port K is, in effect, the inlet port of an atomizing device which comprises a valve member K' carried by a rock shaft K². The latter is journalled at its ends in 70 75

bearings formed in a valve casing member K³ secured to the partition A' at the chamber C side of the latter. The casing member K³ forms one side and the ends of a trough-like valve chamber which is more or less completely closed at its top by the valve member K', according to the angular position of the latter. The valve member K' is biased for movement in the clockwise direction, as seen in Fig. 1, into the position in which its free edge engages a seat portion K⁴ on the casing member K³, and then prevents flow through the port K. The valve member K' is turned counterclockwise to permit flow through the port K, as a result of an excess of the vapor pressure in the chamber B over that in the chamber C. The bias force acting on the valve member K', normally maintains an approximately constant predetermined differential between said two vapor pressures, and thus insures a proper jet velocity between the valve member K' and its seat K⁴, so that the steam subjects the water in the compartment L² to an entraining and atomizing action.

In consequence of that atomizing and entraining action, the stream of steam moving past the valve member K' into the compartment C, carries with it a more or less constant proportion of water, in the form of a mist, which is lifted from the body of water in the compartment L². In any normal position of the free edge of the valve member K, it coacts with the upper edge of the casing member K³ to incline the direction of the stream of steam and atomized water entering the space C, upwardly from the horizontal and away from the partition A'. The atomizing of the water and its distribution throughout the stream insures an intimacy and relatively large area of contact of the water with the steam which is extremely favorable to the rapid and thorough elimination from the water of gases previously contained therein.

The means shown for impressing a bias or loading force on the valve member K' tending to maintain an approximately constant excess of vapor pressure in the space B over that in the compartment C, comprises a lever M external to the tank A and carrying a counter-weight M'. The lever M is carried by a horizontal rock shaft M² which is journalled in a bearing M³ mounted in the side wall of the tank and suitably packed to prevent leakage through the bearing. The lever M might be carried by an integral extension of the valve shaft K², but as shown, each of the shafts K² and M² is detachably connected through a universal joint coupling M⁴ to the adjacent end of a third shaft M⁵, extending between the shafts K² and M². The described separable connection between the shafts K² and M² facilitates assembly and disassembly, and avoids torsional stresses and friction which might otherwise result from the relative thermal expansion and contraction of different portions of the apparatus, and makes it possible to locate the shaft M² with its axis out of alignment from the axis of the shaft K², as may be desirable for practical construction reasons. Advantageously, and as shown, the counterweight M' carried by the lever M is adjustable toward and away from the axis of the shaft M² to thereby vary the torque in the valve closing direction which the lever M impresses on the valve member K'. Advantageously, means are provided to minimize or prevent tendency of the valve member K' to chatter or slam against its seat. The means shown for the purpose comprise a dashpot cham-

ber M⁶ external to the tank A, with a piston M⁷ working therein and connected to the rock shaft M² through a rocking lever M⁸ and link M⁹ connecting a lever M¹⁰ to an arm M¹¹ on the shaft M².

In the apparatus shown, the chemical reagent material is fed into the space B adjacent the bottom of the latter through a supply pipe N extending through the tank wall. For ordinary hot process water softening action, the reagent material supplied by the pipe N is a liquid carrying soda ash and hydrate of lime partly in solution and partly in suspension. No necessity exists for illustrating and describing the means for supplying the reagent material to the pipe N, as such means may be constructed and arranged in any of the well known ways commonly used in hot process water purification systems.

The general operation of the apparatus shown in Figs. 1 and 2 will be apparent to those skilled in the art from the drawings and the foregoing description. The water sprayed into the space B and coming into contact in that space with the steam supplied thereto through the steam inlet J, will be heated nearly to the entering temperature of the steam with the result that the amount of steam condensed in heating the water will be approximately proportional to the amount of water sprayed into the space B. If the steam inlet is supplied with steam at an approximately constant pressure, as is usual in the operation of hot water softening systems, an approximately constant vapor pressure will be maintained in the space B, regardless of the rate at which water is sprayed into that space. The heating of the water as it flows through the space B, will separate from the water the major portion of the air and other gases previously held in solution in the water. In consequence, the atmosphere in the space B will consist of steam mixed with a small amount of gases liberated from the water. The difference between the temperature at which the steam is supplied to the space B and the lower temperature to which the water will be heated in that space, depends upon various factors, and, in general, will increase with the load or rate at which water is supplied, and ordinarily should not exceed 4° F. or 5° F. at heavy loads.

More or less of the gases carried into the sedimentation space with the water entering the latter, and formed in that space as a result of the interaction of the water and reagent material, passes upward into the space B, from the subjacent water, while the remainder is eventually carried into the compartment L² with the water entering that compartment, and is thereafter substantially all separated from the water in the compartment C. The precipitates formed as a result of the interaction of the reagent material with impurities in the water, largely separate out of the water in the sedimentation space in the bottom of which they collect and from which they may be discharged through the usual bottom sludge draw-off connection O.

In the treatment of water of the character ordinarily treated by a hot water softening process, there is little or no tendency for the deposit of impurities from the water in the spray device D, or in the atomizing device including the valve member K', so that the efficiency of the initial heating and final degasification operations are not interfered with by such deposits. There is but little tendency to the deposit of impurities in the spray device D, because the water passes through that device without being heated therein. While the sedimentation action may not

entirely free the water entering the compartment L^2 from precipitated impurities, the impurities carried into and through the compartment L^2 with the water, are not in a form to give trouble by adherence to the atomizing valve structure so as to interfere significantly with the final degasification operation.

The amount by which the vapor pressure in the space B exceeds that in the compartment 10 C, is a function of the loading force on the valve member K', and may be adjusted as conditions make desirable, by adjustment of the counter-weight M' along the length of the lever M. By 15 making that pressure differential sufficiently large, the temperature in the vapor space of the compartment C may be made somewhat less than the temperature of the water in the compartment L^2 , with the result that a portion of the atomized water sprayed into the compartment C, will flash into steam as it passes the valve member K'. Such flashing action is of 20 itself conducive to good deaeration, but in most cases should be kept small or avoided, as it necessarily reduces the temperature at which 25 the purified water is delivered from the apparatus through the outlet H. If the temperature of the water in the compartment L^2 is below the temperature of the steam in the compartment C, the water will be heated substantially 30 to the last mentioned temperature as it is sprayed into the compartment C, as a result of the intimate contact of the steam and water effected by the atomizing valve, and the fact that the atomized water holds too small an amount of dissolved air to significantly retard its heating. 35 When the temperature of the water is thus raised in the compartment C, there is necessarily no flashing action, but, on the contrary, some steam condensation in the chamber C. Such 40 condensation as can occur in normal operation in the chamber C of properly designed apparatus of the character shown, will be so relatively small in amount, that practically all of the steam entering the chamber C will pass out of the 45 latter to the vent condenser F through the outlet I. To insure the thorough elimination of the air and other gases from the water in the chamber C, the thoroughfare flow of steam through the chamber C, should ordinarily amount 50 in weight to about 2½% or so of the weight of water treated, as those skilled in the art of degasifying liquids will understand.

The regulating action of the float E^4 on the water supply valve E^2 , tends to the maintenance 55 of a water level in the chamber C which need vary only through the small range required for the proper adjustment of the supply valve between its wide open and closed positions. To minimize the required over-all vertical dimensions of the apparatus required, and the loss 60 of water head in the apparatus, the minimum water level in the chamber C should be about as high as is practically possible without risk 65 of the water level being carried above the top edge of the valve trough formed by the casing member K³ under such an extreme operating condition as may occur when a heavy load period of operation is followed by a period in which little or no water is discharged through the outlet H. The water level in the compartment L^2 70 will vary but slightly, but the water level in the sedimentation space will necessarily rise slightly relative to the water level in compartment L^2 , as the rate of water supply, or apparatus load,

increases. Regardless of such variations in the height of water level in the compartment L^2 , as may occur in normal operation, the valve member K' will be automatically held in the position required to permit whatever rate of steam flow past the valve member is required to maintain the desired differential between the vapor pressures in the space B and compartment C.

In respect to the initial heating of the water, the addition of reagent material thereto, and 10 the elimination of impurities therefrom by sedimentation, the apparatus disclosed in Figs. 1 and 2 does not differ from ordinary hot process water softening apparatus essentially, except in respect to the economy in space requirements, 15 and the avoidance of heat losses resulting from the incorporation of the initial water heating space in the tank enclosing the sedimentation space. The final degasifying operation, however, 20 is characterized by the effectiveness of the steam atomizing provisions, which break up the water into drops of mist or fog-like dimensions. From such small drops the air and other gases driven out of the solution in the water composing 25 them as a result of the heating of the water to the full temperature of the atomizing steam, may quickly reach the surface of the drops and escape from the latter. Any small gas portions retained by water drops impinging against the roof or side walls of the degasifying 30 compartment C have further and ample opportunity to escape from the water as the latter falls in drops from the roof, or is deflected in drop form from said side walls, or runs down 35 the latter in thin films.

The whole interior of the tank A is effectively used at all times for water storage purposes and to provide steam spaces for heating and degasifying the water. The vertical and horizontal dimensions of the cylindrical tank A shown, which 40 are required for treating water at a given rate, need be no greater with the space above the sedimentation space divided to form separate initial heating and final degasifying spaces as 45 shown, than if all the space above the sedimentation space were used for the initial heating of the water. While the water level in the degasifying space C must ordinarily be lower than the lower level in the sedimentation space, owing to 50 the water lifting action of the atomizing device, the difference in the two water levels is so slight that it represents no significant loss in water head and no consequent increase in the pump energy required to move the water through the 55 apparatus. The high efficiency of the degasifying apparatus due to its atomizing action and to its freedom from the deposit of impurities therein, permit the degasifying apparatus to be of relatively small bulk, and thereby contributes to 60 economy in construction cost, in space occupied and in heat losses to the external atmosphere.

The method of degasification carried out as described with the apparatus shown in Figs. 1 and 2, may obviously be carried out with apparatus differing in form in various respects, and differing in certain of its operating characteristics, from the apparatus shown in Figs. 1 and 2. In particular, as previously explained, the essential principles of the method practiced as described with the apparatus shown in Figs. 1 and 2, may be carried out with apparatus in which all of the steam used in heating and degasifying the water supplied initially to the final degasification chamber, as is provided for in the 75

apparatus shown in Figs. 3, 4, and 5. That apparatus comprises a tank AA divided by partitions A¹¹ and A¹², arranged generally as are the partitions A' and A² of the construction first described, into an initial heating space BA, a final degasification space or compartment CA, and a sedimentation space. Those spaces correspond individually and in their relative arrangement, generally to the spaces B and C and the sedimentation space of the apparatus shown in Figs. 1 and 2. The water to be treated, is supplied to the space BA through a spray device DA which may be identical with the spray device D, but is shown as having its discharge orifices D' arranged at two levels only, instead of at three levels, as shown in Fig. 1. The means shown for supplying water to the device DA at the rate required to maintain approximately constant water level in the compartment CA may be, and are shown as substantially identical with the corresponding means shown in Fig. 1, except for a formal difference in the arrangement of the vent condenser FA. The latter, as shown in Fig. 3, extends through the top wall of the space BA and has its lower portion within said space. F¹⁰ is the vent outlet from the condenser FA.

The water is drawn off from the sedimentation space in the tank AA through a conical collector or draw-off member L as in Fig. 1. From the collector L the water passes as shown in Fig. 3, through a pipe L¹⁰ which opens through the partition A¹² into a cup shaped or flared receptacle L¹¹ within the compartment CA. The receptacle L¹¹ has its open upper end above the normal water level in the chamber CA. The water is atomized and sprayed out of the receptacle L¹¹ up into the steam space of the chamber CA, by steam supplied through a pipe P. The latter delivers to the apparatus all of the steam used in heating and degasifying the water.

All of the steam initially delivered to the chamber CA by the pipe P, except such small portion of the steam as is condensed in the final heating of the water within the chamber CA, passes from the chamber CA into the chamber BA through the port or passage formed by spacing the top of the baffle A¹¹ away from the top wall of the tank AA. Baffles A¹³, depending from the top wall of the tank at each side of the baffle A¹¹, prevent the water from being sprayed from either of the chambers BA and CA into the other chamber. All of the gases liberated from the water in the apparatus pass from the chamber BA into the vent condenser, and thence out through the outlet F¹⁰.

The means shown in Figs. 3, 4, and 5 for atomizing the water entering the chamber L¹¹, comprises a spray head Q which is of inverted bell or cup form and is carried by a rod Q⁹. The latter is shown as axially disposed within the steam supply pipe P. The latter extends downwardly into the compartment CA through the top wall of the tank AA, and has its lower end beveled for engagement with the conical valve seat Q' formed on the inner wall of the member Q adjacent the lower end of the latter. The steam, which in normal operation is discharged from the pipe P through the space between its lower end and the seat Q', is delivered into the lower ends of channels Q² formed in the atomizer Q. As shown, there are four channels Q², each of which in horizontal cross section is an annular arc of a little less than 90°. The outer wall of each channel

Q² is formed by the conical outer shell portion of the chamber Q. The adjacent walls Q³ of adjacent channels Q² are shown as radial, and the inner wall Q⁴ of each channel is shown as formed by a section of a hollow cone coaxial with the outer wall of the member Q. Each wall Q⁴ terminates at its upper end in a weir edge Q⁵ and merges at its lower end into a tubular portion Q⁶, which forms a guide sleeve receiving the pipe P.

The adjacent end walls Q³ of adjacent channels are spaced apart to form radial water inlet channels Q⁷ open at their outer edges. These channels supply water to the adjacent ends of troughs Q⁸, there being one of these troughs between the inner wall Q⁴ of each channel Q² and the adjacent portion of the sleeve Q⁶. The upper weir edge Q⁵ of each wall Q⁴ is downwardly inclined slightly from each end towards its middle, so that at low loads the water inflow into the channel Q² is concentrated at the central portion of that channel, whereas at heavier loads the inflow of water to each channel is distributed along the whole length of the wall Q⁴. At overloads water may enter each channel Q² over the downwardly inclined upper edges of the corresponding end walls Q³ and over the horizontal upper edge of the outer wall of the channel.

The member Q is subjected through its supporting rod Q⁹ to a valve seating force adequate to insure the desired jet velocity of steam discharge through the annular space between the lower end of the pipe P and the seat Q', the member Q thus serving in effect as a loaded back pressure valve controlling the downflow of steam through the pipe P. The pressure drop past said valve or excess of pressure in the pipe P over that in the compartment CA may obviously vary with conditions of use, and under ordinary conditions may well be in the neighborhood of a pound per square inch. The magnitude of that pressure is determined in the apparatus shown in Figs. 3, 4, and 5 by the action of valve loading means and analogous to those employed in conjunction with the valve member K' of the apparatus previously described. The loading means shown in Fig. 3 comprises a rock shaft M¹⁰ carrying a lever arm M¹¹, to which the upper end of the rod Q⁹ is link connected, and having an oppositely extending lever arm M¹² which carries an adjustable counterweight M¹³. Another lever arm M¹⁴ carried by the rock shaft M¹⁰, is link connected to the upper end of the stem of a dashpot piston M¹⁴ working in a dashpot chamber M¹⁵ and operating to minimize any tendency to chattering movement or slamming of the device Q. A cup-like extension M¹⁶ at the upper end of the chamber M¹⁵ collects water of condensation and thereby keeps the chamber M¹⁵ filled with liquid.

The water level in the portion of the compartment CA surrounding the basin L¹¹ rises and falls as required to give the float E⁴ a suitable control range of movement between its upper light load and lower heavy load positions. While the water level in basin L¹¹ falls relative to the level in space BA slightly as the load increases, the parts may be so proportioned that this fall in water level is quite small. The water level in space BA indicated by line a in Fig. 3, varies but little with changes in load, as but little loss of head is required to maintain the heaviest load flow of water into the channels Q⁴. Moreover, such loss of head is compensated for somewhat

by the fact that the member Q is lowered as the load is increased. The energy required to lift the water from the steam spray device Q into the space above the basin L¹¹ is furnished by the atomizing steam and adds nothing to the load on the pumping machinery required to put the water into the apparatus through the supply pipe E and spray pipe DA.

As will be apparent from what has already been said, the apparatus shown in Figs. 3-5 has the same general mode of operation and gives the same general advantages as the apparatus shown in Figs. 1 and 2. With each construction, all of the space within the enclosing tank is effectively and efficiently used, so that the bulk and height of the tank required for a given duty, or capacity, are kept desirably small. With each construction the energy of the steam used in atomizing and spraying the water into the final degasifying stage gives an upward movement to the atomized water and thereby aids in keeping the height of the apparatus relatively low and in minimizing the loss of head of the water moving through the apparatus, and consequently in minimizing the pumping energy required for moving the water through the apparatus. Each construction permits of the simplification in piping resulting from the supply of all the steam used in the initial heating chamber and in the final degasifying chamber, initially to one of those chambers through a single steam supply pipe. With each form of construction, interference with the heating and degasifying operation by deposited impurities carried into the apparatus by the water treated, are substantially avoided. With each form of construction, the hot process method of water purification may be carried out as effectively and efficiently as in the best forms of apparatus heretofore in use for the purpose, without requiring any significant increase in bulk or height of the tank to obtain the additional advantage of efficient degasification within the tank which has not been obtained with the apparatus heretofore used in the hot process of softening water. The increased apparatus cost required for the degasifying operation is confined practically to the cost of the relatively inexpensive apparatus for spraying the water into the final degasification chamber.

While the two forms of construction illustrated are alike in general mode of operation and advantages obtainable, as stated above, they differ in certain specific operative features, and each form has some advantage over the other under certain specific conditions of use. Thus, in the form last described, the vapor pressures in the chambers BA and CA are substantially the same at all times, and the treated water may be delivered from the chamber CA at the full temperature of the steam supplied, which, of itself, is ordinarily desirable. In the form shown in Figs. 1 and 2, the vapor pressure in the chamber C is necessarily a pound or so lower than in the space B, so that the temperature of the water delivered from the chamber C, which corresponds to the vapor pressure in the chamber C, must be a trifle below the temperature of the steam initially supplied to the space B. In ordinary practice, however, there will ordinarily be no significant difference in the relation between the temperature in the steam supply pipe and the water delivery temperature between the two forms of apparatus described. Since in the apparatus shown in Fig. 3, the atomizing operation requires a steam pressure drop

of a pound or so in the steam as it passes from the pipe P into the compartment CA, no such pressure drop is required in the passage of the steam through the inlet J of Fig. 1. In each construction, therefore, the pressure in the final degasifying compartment may be lower than the steam supply pipe pressure only by the amount of a pound or so due to the drop in pressure in the deaerating atomizer. Means for atomizing the water and spraying it into the final degasifying chamber may ordinarily be somewhat simpler with the construction shown in Figs. 1 and 2, than with the construction shown in Figs. 3-5. In some cases, moreover, the flashing operation possible with the construction of Figs. 1 and 2, is desirable.

Novel apparatus features shown in Figs. 3, 4, and 5 of the appended drawings, and hereinbefore described, are not claimed herein, but are claimed in my prior application Ser. No. 647,878 filed December 19, 1932, of which the present application is a continuation in part.

While in accordance with the provisions of the statutes, I have illustrated and described the best forms of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. In heating and degasifying water by bringing the water into contact with steam and by adding to the water a chemical reagent reacting with hot water to precipitate impurities therefrom, the method which consists in passing the water through a steam space into a sedimentation space beneath said steam space, thence upward from the sedimentation space into a second steam space, supplying steam to the first mentioned space to heat the water passing through that space, and subjecting the water passing from the sedimentation space to an atomizing steam jet action spraying the entering water upward into the second mentioned steam space.

2. In heating and degasifying water by bringing the water into contact with steam and by adding to the water a chemical reagent reacting with hot water to precipitate impurities therefrom, the method which consists in passing the water through a steam space into a sedimentation space beneath said steam space, thence upward from the sedimentation space into a second steam space, and heating the water passing through the first mentioned space and subjecting the water passing from the sedimentation space to an atomizing steam jet action spraying the entering water into the second mentioned steam space, effecting such heating and atomizing action with steam supplied initially to one of said steam spaces, passing steam not condensed in the steam space to which it is initially supplied, and gases liberated therein from the last mentioned space into the other of said steam spaces and withdrawing gases from the last mentioned space.

3. In heating and degasifying water by bringing the water into contact with steam and by adding to the water a chemical reagent reacting with hot water to precipitate impurities there-

from, the method which consists in passing the water through a steam space into a sedimentation space beneath said steam space, and thence upward from the sedimentation space into a second steam space, supplying steam to the first mentioned steam space to heat the water passing through that space, supplying steam to the second mentioned steam space to subject the water passing into the latter from the sedimentation space to an atomizing steam jet action spraying the water into the last mentioned steam space, and removing gases separating from the water from said steam spaces.

4. Water purifying and deaerating apparatus comprising in combination, a treatment chamber having an upper steam space and a submerged water outlet, an outflow chamber having a water outlet and a separate air and vapor outlet, means for passing water to be treated into said steam space, means for supplying steam to said steam space in excess of the amount condensed in heating the water introduced into said space, and a deaerating atomizer receiving water to be atomized from the first mentioned outlet and receiving atomizing steam from said steam space and discharging the atomized water into said outflow chamber.

5. Water purifying and deaerating apparatus comprising in combination, a treatment chamber having an upper steam space and a submerged water outlet, an outflow chamber having a water outlet and a separate air and vapor outlet, means for passing water to be treated into said steam space, means for supplying steam to said steam space in excess of the amount condensed in heating the water introduced into said space, and a deaerating atomizer receiving water to be atomized from the first mentioned outlet and receiving atomizing steam from said steam space and discharging atomized water into said outflow chamber, said atomizer including automatic throttling means for maintaining a pressure in said steam space in predetermined excess over the vapor pressure in said outflow chamber and thereby maintaining a suitable atomizing steam velocity in said atomizer.

6. In water purifying and deaerating appara-

tus, the combination with a tank structure enclosing a sedimentation space constituting the major portion of the tank interior, of partition means dividing the upper portion of the tank space into a degasifying compartment and an initial heating chamber alongside said compartment and open at its lower end to said sedimentation space, said compartment having an outlet for treated water and a separate outlet for vapors and gases, means for supplying steam to said heating chamber, a deaerating atomizer receiving water to be atomized by gravitational flow from said sedimentation space and receiving from said chamber steam for atomizing the water received and discharging atomized water upwardly into said compartment, and means for supplying water to be treated to said chamber as required to normally maintain the water level therein at the level required for the described reception of steam and water by said atomizer.

7. In water purifying and deaerating apparatus, the combination with a tank structure enclosing a sedimentation space constituting the major portion of the tank interior, of partition means dividing the upper portion of the tank space into a degasifying compartment and an initial heating chamber alongside said compartment and open at its lower end to said sedimentation space, said compartment having an outlet for treated water and a separate outlet for vapors and gases, means for supplying steam to said heating chamber, a deaerating atomizer receiving water to be atomized by gravitational flow from said sedimentation space and receiving from said chamber steam for atomizing the water received and discharging atomized water upwardly into said compartment, said atomizer including means automatically adjustable to maintain a vapor pressure in said chamber in predetermined excess of the vapor pressure in said compartment and thereby maintain an atomizing velocity of the steam received by said atomizer from said chamber, and means for supplying water to be treated to said chamber as required to normally maintain the water level therein at the level required for the described reception of steam and water by said atomizer.

VICTOR A. ROHLIN.
